UNITED STATES PATENT OFFICE.

WILLIAM S. NEWTON, OF GREENVILLE, CONNECTICUT.

IMPROVEMENT IN PEGGING-AWLS.

Specification forming part of Letters Patent No. 173,660, dated February 15, 1876; application filed January 29, 1876.

To all whom it may concern:

Be it known that I, WILLIAM S. NEWTON, of Greenville, in the county of New London and State of Connecticut, have invented certain new and useful Improvements in Pegging-Awls; and I do hereby declare the following to be a full, clear, and exact description of the invention, such as will enable others skilled in the art to which it pertains to make and use it, reference being had to the accompanying drawings, which form part of this specification.

My invention relates to an improvement in pegging-awls; and it consists in the arrangement and combination of parts that will be more fully described hereinafter.

The accompanying drawings represent my invention.

a represents the stock, having an enlarged head, *c*, upon which are fastened a number of pieces of leather, *d*, so as to prevent the hammer from striking the iron head. Upon the lower end of the stock is formed the usual clamping device *e* for holding the awl. Inclosing this stock is the cylindrical handle *g*, the upper end of which is screwed to the head of the stock *c*, as shown, while upon the inner edge of the other end is formed the flange *i*, which serves as a stop for the extractor *h*. This extractor has a flange around its upper edge, which catches against the flange *i*, and prevents it from being forced out of the handle, while its other end forms a flat bearing-surface that bears upon the leather as the awl is driven in. Through opposite sides of this extractor are made the openings

j, so as to give ready access to the clamp *e*, which projects down below the lower edge of the cylinder *g*. By means of these openings the clamp can be opened and closed at will for the purpose of changing the awls without having to remove or take apart any of the whole device. In one edge of the lower end is cut a V-shaped notch, *o*, which enables the operator to see just where to put his awl. Placed inside of the handle surrounding the stock is the coiled spring *2*, which bears against the head *c* at one end, and on top of the extractor at the other. When the awl is driven into the leather a sufficient distance to force upward the extractor into the handle the spring becomes compressed, and bearing down upon the extractor with all its force the strength of this spring is used in extracting the awl from the leather.

Having thus described my invention, I claim—

1. A pegging-awl, having an extractor that has its lower end closed, and an opening in its side so as to see where to put the awl, substantially as shown and described.
2. The combination of the stock *a*, head *c*, handle *g*, extractor *h*, flanges and spring, substantially as described.

In testimony that I claim the foregoing I have hereunto set my hand and seal this 19th day of January, 1876.

WM. S. NEWTON. [L. S.]
